Filed July 21, 1965, Ser. No. 473,637

11 Claims. (Cl. 239—100)

ABSTRACT OF THE DISCLOSURE

A road striping device with a gear train connected through a clutch to a measuring road wheel drive providing electrical switching for applying solid or intermittent stripes through use of automatic reset cams and switches, advance-retard switching with incremental adjustment of the length of the line through use of cams and micro-switches, clutching and brake arrangement, and multiple switching arrangements.

The present invention relates to highway line spraying apparatus having an electrical control for various line patterns, and more particularly includes means for introducing an adjustable increment into a mechanically driven electrically controlled intermittent cycling device.

It is the practice to place markings or indicating lines along the center of a highway or between the lanes of a multi-lane highway. In order to rapidly and economically apply the desired lined pattern, it is necessary that equipment be provided that is capable of laying down or spraying a number of different line patterns. It is also necessary that the equipment be such as to enable the operator to apply a new line on the highway that will coincide with the existing intermittent line when refreshing lines that are still visible, have not been completely obliterated by traffic and weather conditions.

It is therefore an object of the present invention to provide a highway line spraying apparatus having an adjustable increment of spraying time, which increment may be either an increase or decrease of the normal intermittent cycle during which paint is sprayed.

It is also an object of the present invention to enable the increment to be introduced in multiple during the same cycle.

The present invention as used with highway line spraying apparatus makes it possible for the operator of the vehicle to estimate the difference between the existing intermittent line and the new line he is applying and compensate for this difference in measured known increments with a high degree of accuracy.

In the apparatus of the present invention, a known adjustable amount of increment can be manually or automatically introduced into the memory system which carries out the desired change of the intermittent cycle.

Basically the present invention includes a mechanism having a gear train connected through a clutch to a measuring road wheel drive which provides a normal cycle for applying a paint stripe to the road. When an intermittent cycling unit is operated the gear train is then engaged and through a reset means is automatically reset to an initial point each time the painting of the intermittent line is completed. Through advance-retard switching means the registration of the new line is made to match the existing old line and coincides with the old

2

line throughout its entire length by incremental adjustment of the length of the new line.

The above and other objects and advantages of the invention will become apparent upon full consideration of the following detailed description and accompanying drawings in which:

FIG. 1 is a circuit diagram of the electrical system embodied in the present invention with mechanical interconnections thereto;

FIG. 1a is a diagrammatic illustration of the various line patterns produced by the present invention and their relation to the circuit controlling switches illustrated in FIG. 1; and

FIG. 2 illustrates an alternate embodiment of the mechanical portion of the system of FIG. 1.

Referring to the drawings and particularly FIG. 1, a ground wheel 10 is illustrated therein and it is understood that the ground wheel 10 is to be rotatably mounted on a vehicle for applying markings to a highway or road.

The ground wheel 10 may be one of the drive wheels for the vehicle or may be separately mounted thereon. The vehicle on which the ground wheel 10 is rotatably mounted may be of any conventional style now in use for applying road striping and accordingly may be of the self-propelled or trailer type used for this purpose. The road striping vehicle normally carries thereon containers for the paint binder and glass reflecting spheres, a compressor, an internal combustion engine, paint gun and sphere dispensers. The paint guns are diagrammatically illustrated in FIG. 1 at 11, 12, 13 and 14 and it is understood that they will communicate in the usual fashion with the air compressor and paint binder container through suitable conduits.

The line striping apparatus embodied herein is adapted to apply a continuous or interrupted line and since several paint guns 11-14 are utilized, variations of the interrupted and continuous line are adapted to be applied, some of these variations being illustrated in FIG. 1a.

In order to control the operation of the paint guns 11-14 an electrical circuit shown in FIG. 1 is employed, the electrical circuit being adapted to automatically control the paint guns to effect the desired striping operation.

Since the striping operation is dependent on the travel of the striping vehicle, a direct drive is provided from the ground wheel 10 to the paint gun control means. The circuit drive includes a drive pulley 15 that is driven by the ground wheel 10 through a belt 16, the shaft of the ground wheel 10 also including a pulley (not shown) that operatively engages the belt 16. Drive pulley 15 is mounted on shaft 17 turning said shaft and kick cam 18, pulse cam 19 and gear 21 mounted thereon. Kick cam 18 is mounted on shaft 17 so as to lead pulse cam 19 in rotation of both cams. Gear 22 mounted on input shaft 23 to the brake and clutch assembly 24-25 is a relative large gear driven by gear 21 mounted on the opposite end of shaft 17 from drive pulley 15.

A differential 30 has gears 31 and 32 thereon turned respectively by gear 26 on the output shaft of clutch 25, and gear 33 mounted on shaft 34 connected to the armature of motor 35. Mounted on shaft 36 which is connected to differential gear 32 are reset cam 37 and skip cam 38.

Each of kick cam 18, pulse cam 19, reset cam 37 and skip cam 38 have micro-switch contacts 41-44, respectively operated by the respective cams. Follower 41a rides

on the edge of kick cam 18. Kick cam 18 has a lobe on its periphery just large enough to close the contacts 41a-41b when follower 41a rides on the lobe. Pulse cam 19 is a split lobe cam in which the percentage of lobe on the cam can be varied by spreading the separate lobes or closing them together to an overlapping position. Follower 42a rides on the peripheral edge of pulse cam 19 and causes a closing of contacts 42a and 42b when the follower 42a rides on the lobes. Reset cam 37 having a recess in the periphery thereof has follower 43a riding the edge of the cam with contacts 43a-43c closed when follower 43a is within the recess and alternatively contacts 43a-43b closed when follower 43a rides the remaining edge of reset cam 37 outside of the recess. Mounted on the outer end of shaft 36 for rotation with reset cam 37 is a skip cam 38 whose lobe thereon determines the skip line cycle and whose setting in relation to reset cam 37 determines the beginning of the skip line cycle. Follower 44a responsive to the rotation of skip cam 38 causes a closing of contact 44a-44b when follower 44a rides on the lobe of skip cam 38. Skip cam 38 may be a split cam similar in construction to cam 19 and thus could be adjusted as to the portion of the total cycle during which painting takes place, this portion being variable because of the split nature of the cam.

Referring now to the electrical circuit portion of FIG. 1, which operates in conjunction with the mechanical portion described above, the electrical circuit for controlling the operation of paint guns 11-14 is illustrated as including a power source such as a battery 46, that may be the battery of the vehicle on which the striping equipment is mounted. The battery 46 is connected to ground and also through the ignition of the vehicle to an on-off relay 47, and through a fuse 48, to a conductor 49 connecting to a main switch 50 of the three pole single throw type.

One set of contacts 51 of the switch 50 connects the conductor 49 to conductor 52 that in turn is connected with the multi-station switch indicated generally as 100 within the control box, the conductor 52 forming a part of the power feed for the circuit. The conductor 49 is also connected through a set of contacts 53 to contact 44b operated by skip cam 38 and to the center contact of take-out memory relay 60. Conductor 52 through contacts 51 connects conductor 49 to ground through an indicating light 54. The light 54 is conveniently mounted on the same panel as the multi-station switch 100 and serves to indicate when voltage has been applied to the switch 100 and is available to operate the unit.

A second indicating light 55 is connected in series with contact 43c of the micro-switch operated by reset cam 37 and serves to indicate a completed circuit in the reset system and thus indicates when the skip line unit is in a reset position and ready to operate. A third pair of contacts 56 connects follower contact 44a, operated by skip cam 38, to a conductor 57 forming a part of the circuit for supplying skip power during the skip cycle, as will be described hereinafter.

The multi-station switch 100 has eight separate operators illustrated and each of these operators controls either one, two or three sets of contacts as will be apparent hereinafter. The conductor 52 is connected with conductors 91 and 92 of the switch 100. Conductors 93, 94, 95 and 96 are respectively connected to the valve operating solenoids of spray guns 11, 12, 13 and 14 respectively.

For the purposes of illustration the circuitry has been set up to control a left spray gun 11 for spraying a yellow stripe, a right spray gun 13 for also spraying a yellow stripe, and two center spray guns 12 and 14 arranged in tandem to spray yellow and white stripes respectively. The number of spray guns and the colors used are merely illustrative and are not meant to limit the number of spray guns since either more or less than four spray guns may be used with the present invention. Only eight operators have been illustrated in FIG. 1 but by the addition of

more operators with additional contacts with connections to the conductors 93-96 leading to the spray gun solenoids and to the conductors 97-98 supplying skip power, each of the spray guns could be controlled as is spray gun 14 to spray intermittent lines or continuous lines as desired.

Also connected to each of conductors 93-96 are relay solenoids 71-74, respectively, which operate their respective relay contacts to operate counters 75-78 which record the amount of spraying time in units of distance sprayed for each of spray guns 11-14. One of each of the relay contacts is connected to a counter solenoid with the opposite contact supplied with 12 volt pulsed power. Counters 75-78 operate one count for each pulse supplied and therefore in the system illustrated an individual counter will operate a count for each pulse supplied to the counter during the operation of the spray gun associated with that counter. An additional pulse cam 20 driven by road wheel 10 operates contacts with one contact connected to a 12-volt source through main switch 50 and the other contact connected to relay contacts of solenoids 71-74, thereby supplying the pulse power to each one of the relay contacts as shown. This enables the counters to measure in feet, yards, or portions of a mile regardless of road speed with minimal error since there is a correlation with road speed of one pulse per unit of distance.

In the circuit for controlling the operation of the spray guns 11-14 conductors 93-96 in multi-station switch 100 are connected by the separate operators either to conductors 91 or 92 when a solid line or lines are to be applied such as illustrated by patterns 1, 2 and 6 or to conductors 97 or 98 supplying skip power when only a skip line is to be applied such as illustrated by pattern 5. Other operators connect one spray gun to a conductor 91 or 92 and another spray gun to a conductor 97 or 98, thereby having a solid line sprayed by one spray gun while an intermittent line is sprayed by the other, such as illustrated in patterns 3 and 4. In each case upon the operation of a separate operator a connection is made from the 12-volt line of conductor 92 to either conductor 101 or 102 dependent upon whether or not an intermittent line or solid line is to be sprayed. If an intermittent line is to be sprayed then connection is made to conductor 101.

Referring to the multi-station power switch 100, switches 120, 121 and 122 are connected for movement together and are moved by a common operator or key. It is seen that closing of the switch 120 will connect conductor 93 with conductor 91, and that closing of switch 121 will connect conductor 94 with 91, and closing of switch 122 will connect conductor 102 with 92. In a similar manner each key or operator operates one of the following groups of switches namely, 123-125, 127-129, 131-133, 135-136, or 137-138. Switch 139 in the multi-station switch 100 is utilized when it is desired to merely reset the circuit. The circuit illustrated in FIG. 1 also provides for retarding or advancing the line pattern during the intermittent or skip line applying operation. In conjunction with this operation the circuit also provides for incremental increases or decreases in the length of the intermittent line. For these purposes there is included in

the circuit advance-retard switch 62 for advancing or retarding the intermittent line in the direction of the vehicle. Also a take-out memory relay 60 and initial memory relay 61 are each multi-position relays with rotating center contacts 64 and 65, respectively. Solenoids 66 and 67 of relays 60 and 61, respectively, rotate the respective center contacts of each relay from position to position one increment at a time. These relays are connected in a parallel manner so that their multiple positions are wired where each is in phase with its comparable unit. Also the 70 rotating center contacts 64 and 65 operate in phase. Solenoid 67 is connected to contacts 68 and 69 of advance-retard switch 62. Thus solenoid 67 of initial memory relay 61 is pulsed through operator controlled advance-retard switch 62. Solenoid coil 66 of take-out memory 75 relay 60 is pulsed by the kick cam micro-switch through

contacts 41a-41b and the contacts of advance-retard operation relay 80 and contacts 81 of motor operational relay 82 as the unit either advances or retards. Due to these connections both relays 60 and 61 are in phase at all times, except when the memory circuit is in use. Through this circuitry the memory system can count in and take out pulses as they are applied to the corrected cycle. Examining the circuitry in further detail, it will be noted that the initial memory relay coil 67 is pulsed one time for each operation of the advance-retard switch 62. Voltage flows through the center contact 64 of the take-out memory relay 60 and to the initial memory relay 61, then out through the center contact 65 of the initial memory relay 61 and to the coil of advance-retard operation relay 80. This voltage may flow at any time that the rotating center contacts 64-65 of relays 60-61, respectively, are aligned. This is the normal condition when the unit is not advancing or retarding. The take-out memory relay 60 is operated by the same voltage supplied to the coil of motor operational relay 82. For each pulse which is put in by the advance-retard switch 62 the system operates one increment and the take-out memory relay 60 moves back one increment towards alignment.

The operation of reset relay 83 will be discussed further in connection with the operation of the system but this relay has as its sole purpose to return the unit to a zero position when not in use. In doing this it disconnects the advance-retard system from the skip line circuitry.

Motor direction control relay 84 in the circuit is connected so as to reverse the ground and apply voltage to the motor leads as necessary to determine the direction of rotation of motor 35.

Operation

The power for the circuit is supplied by actuating main switch 50 which closes contacts 51, 53 and 56. Assuming that solid or continuous lines are to be applied by spray guns 11 and 12, as indicated by pattern No. 1 in FIG. 1a, the operator depresses the button for switches 120, 121 and 122. Power from battery 46 is then supplied to the solenoids of spray guns 11 and 12 through conductor 49, switch contacts 51, conductors 52, conductor 97, switches 120 and 121 to conductors 93 and 94 respectively. Power is also supplied from conductor 52 through switch 122, conductor 102, through reset relay 83 to a reset speed rheostat but there is no action since the gear train is engaged only when intermittent or skip painting takes place.

If an intermittent or skip line is to be applied, for example as by spray gun 14 illustrated by pattern No. 5 in FIG. 1a, switches 135 and 136 are closed. Power to the solenoid of spray gun 14 is supplied through conductor 49, main switch contacts 53, micro-switch contacts 44b-44a on skip cam 38, main switch contacts 56, conductors 57, conductor 97, switch 135 and conductor 96. In order to drive the cam 38 to cause the microswitch 44 to intermittently break the circuit to the solenoid of spray gun 14 and thus apply the skip line, the clutch 25 must be energized. Power to clutch 25 is supplied through conductor 49, main switch contacts 51, conductor 52, to conductor 92, through switch 136, conductor 101, to clutch 25. The clutch 25 is thus energized to cause gear 26, differential 30, shaft 36 and cam 38 to be rotated, thereby interrupting the circuit through switch contacts 44a-44b as determined by the contour of the cam 38 with the operation of micro-switch 44 controlled by the rotation of the cam 38.

When an intermittent line is being applied it is desirable at times to add incremental advancing or retarding changes into the circuit. In such case shaft 17 is driven by ground wheel 10 through belt 16 and drive pulley 15, thereby correlating the paint spraying with the road speed of the vehicle. This input is connected to reset cam 37 and skip cam 38 through clutch 25 and brake 24 and differential 30. Skip cam 38 rotates one revolution per

cycle as may be desired by the operating crew. The lobe of skip cam 38 operates a micro-switch 44 with contacts 44a and 44b which close while follower 44a rides on the lobe of skip cam 38 and which allows the operation of the respective spray gun or guns upon the closing of contacts 44a-44b. The portion of the cycle during which the spray guns are operated may be varied to conform to irregularities in prior paint application which are presently on the road and which the operator is trying to retrace. In such case motor 35 is engaged through differential gear 32 to the shaft 36 to rotate it ahead in its normal direction of rotation or alternatively in reverse while clutch 25 is disengaged and brake 24 holds gear 31 of differential 30 motionless through gear 26, thus lengthening or shortening the total cycle compared to the actual travel on the road.

Differential 30 which is attached on shaft 36 controlling the movement of skip cam 38 and reset cam 37 is connected to the motor 35 through its gear 32 and motor gear 33. This motor 35 is multi-directional and will drive the shaft 36 in either direction regardless of the input direction from road wheel 10 or other measuring device. This motor 35 adds the advance or retard increment as desired. The only difference between an advance or retard increment is the direction of motor 35 operation. Each side of motor 35 is grounded to a variable resistor so that the speed in one direction may be different from the speed in the other direction. This is necessary for any minor adjustments due to the peculiarities of operation of each individual unit.

When tracing an increment of change, either advance or retard, through the system, the following actions occur. When the advance-retard switch 62 is operated in either direction a pulse is sent to initial memory relay 61 through solenoid coil 67. This throws rotating center contact 65 one step out of phase with rotating center contact 64 of take-out memory relay 60 and deenergizes the coil of advance-retard operation relay 80. The function of this relay is to permit voltage to appear in the advance-retard circuit particularly at micro-switch 41. At contacts 41a-41b operated by kick cam 18, the voltage at these contacts, when follower 41a passes over the lobe of kick cam 18, passes through the solenoid coil of motor operation relay 82. When this relay is operated voltage is permitted to the contacts 42a-42b operated by pulse cam 19 and to the rest of the circuit which drives the motor 35. At the same instant that the advance-retard switch 62 is operated and a pulse is sent to the initial memory relay 61, a pulse is also sent to one of the two coils A or B of motor direction control relay 84 connecting one set of contacts through operation of coil A and a second set of contacts through operation of coil B depending through which coil the voltage is fed. Relay 84 simply governs the direction of rotation of the advance-retard motor 35 by connecting voltage to one side of the motor and ground to the opposite side of the motor. When the direction of motor rotation is desired to be changed the motor direction control relay 84 is thrown in the opposite direction by application of voltage to the opposing coil and the ground and control voltage are applied to the opposite terminals of the motor.

Pulse cam 19 holds the circuit in operation for a specified length of time until motor 35 has completed the change in degrees of rotation of skip cam 38. This pulse is adjustable in length due to the split lobe cam construction of pulse cam 19 by which the amount of lobe can be varied by spreading the separate lobes or closing them together. This variation in lobe spread regulates the time the motor 35 is running and therefore the increment length. The pulse cam 19 is correlated with the kick cam 18 in such a manner that as soon as kick cam 18 has operated the motor operation relay 82, the pulse cam 19 through microswitch contacts 42a-42b picks up the motor operation relay 82 coil circuit and holds it in operation for a given length of time. Pulse cam 19 cannot start in

the middle of the lobe because kick cam 18 must be operated first. This would mean that the shaft must rotate a portion of the cycle if the initial increment is pulsed into it while the follower 42a which rides on pulse cam 19 is at a point after the initial point of the lobe on pulse cam 19.

After the follower 42a passes over the lobe of pulse cam 19, contacts 42a-42b are opened which drops the motor operation relay 82 out of the circuit, opening all contacts therein.

When the micro-switch contacts 41a and 41b were closed by kick cam 18 initially, thereby operating motor operation relay 82, the take-out memory relay 60 was also pulsed through motor operation relay 82 causing it to move back into phase with initial memory relay 61 and energizing the coil of the relay 80 which caused the circuit voltage to open, cutting voltage off the advance-retard circuit. When the initial memory relay 61 is pulsed several times, take-out memory relay 60 will receive a pulse every time the motor operation relay 82 operates until it has returned in phase with initial memory relay 61.

The initial memory relay 61 may be automatically pulsed instead of depending upon manual operation of the advance-retard switch with increments added by placement of a pulser, similar to a telephone dial, in series with advance-retard switch 62 and solenoid coil 67. Any multiple of an increment may then be pulsed into the system automatically in lieu of manual means. This would entail no change in the operation of the system as described above.

The measured increment device described above will work equally well in variations of the systems for putting down intermittent paint lines on the road. For example, a double clutch system could be substituted for the brake 24, clutch 25, and motor 35 of the present system. In such an alternate system illustrated in part in FIG. 2, a clutch 201 replaces both clutch 25 and brake 24 while a second clutch 202 replaces the electric motor 35. Differential 30 is eliminated and the second clutch 202 is connected to gear 203 which turns shaft 36 with reset cam 37 and skip cam 38 mounted thereon through gear 204 on the output of second clutch 202. First clutch 201 has a gear 205 mounted on its output so as to also be able to rotate gear 203. Gears 206 and 207 are mounted on the inputs to clutches 201 and 202 respectively and are both in rotating contact with gear 21 which, as previously described in regard to FIG. 1, is rotated through connection to ground wheel 10.

Gear 206 is larger than gear 207 and therefore since both are rotated by the same gear 21, the output gear 204 of second clutch 202 rotates at a greater speed than output gear 205 of first clutch 201. Therefore, when it is desired to increase the speed of shaft 36 carrying cams 38 and 37 thereon, as was previously done by motor 35, in cooperation with brake 24 and clutch 25, the first clutch 201 is disengaged and second clutch 202 having the greater output speed of rotation is engaged. When it is desired to slow down shaft 36, both clutches 201 and 202 are disengaged for a moment and then first clutch 201, which is the normal drive clutch, is engaged and shaft 36 is rotated at a normal speed.

The electrical system connected to the double clutch system illustrated in FIG. 2 is substantially similar to that illustrated in FIG. 1 with minor changes. The connections to clutch 25 are made to clutch 201 so as to allow the engagement of clutch 201 for normal skip pattern painting. The connections to the brake 24 are eliminated. The retard voltage connections made to motor 35 in FIG. 1 are instead connected to clutch 202 in FIG. 2 so that skip cam 38 turns faster when retarding. The connection 208 between relay contacts of motor direction control relay 84 is opened removing the ground from the advance con-

tacts of relay 84 so that the circuit through clutch 202 is not complete, and therefore clutch 202 does not engage. The advance-retard speed rheostat is also deleted for the circuit of FIG. 2. When the advance section of advance-retard switch 62 is operated it will also activate a coil 210 by closing of a switch 211 supplying voltage from the same source of current supplying the coil of relay 80. A connection is made at point X in the circuit for this current-source. Contact 212 operated by coil 201 is in the line to clutch 201. The circuit of FIG. 1 with the changes discussed above thereby completes the circuitry of FIG. 2 and operates the double clutch system. Conductors 1' through 7' in FIG. 2 extending from reset relay 83, are connected as conductors 1' through 7' shown in FIG. 1 with equivalent circuit connections.

It will be obvious to those skilled in the art that various changes may be made without departing from the scope of the invention and therefore the invention is not limited to what is shown in the drawings and described in 20 the specification but only as indicated in the appended claims.

What is claimed is:

1. Road striping apparatus comprising a plurality of spray guns, solenoid means for controlling the operation of said spray guns, an electrical circuit electrically connected to said solenoid means for controlling the operation thereof, said electrical circuit including a power supply, a multi-station switch connected to said power supply, a skip circuit including a skip switch responsive to movement of road striping apparatus and operable to cause said spray guns to spray an interrupted line through a predetermined skip cycle, a reset circuit including a reset switch for automatically resetting the skip cycle, said multi-station switch including a plurality of sets of contacts that are electrically connected to said spray guns and said skip and reset circuits, each set of contacts defining a predetermined striping pattern and controlling the operation of said electrical means to control the application of said pattern by said spray guns, means for advancing and retarding said interrupted line sprayed by said spray guns, and means for incremental adjustment of the length of said interrupted line sprayed by said spray guns.
2. Road striping machinery comprising a ground wheel rotatably mounted on said machine, a plurality of spray guns mounted on said machine, an electrical circuit responsive to movement of said ground wheel for controlling the operation of said spray guns, a first cam means operatively connected to turn proportionately to the rotation of said ground wheel, electromagnetic clutch means electrically connected to said electrical circuit and adapted to be operatively connected to said ground wheel, a differential having one side operatively connected to said electromagnetic clutch means, a bi-directional motor operatively connected to the opposite side of said differential, a second cam means connected to said opposite side of said differential and responsive to the rotation thereof, said electrical circuit including a power supply, a multi-station switch connected to said power supply, a skip circuit, reset circuit, kick circuit and pulse circuit, said skip circuit including a switch responsive to

movement of said second cam means for intermittently controlling the operation of said guns, said reset circuit responsive to movement of said second cam means for automatically resetting the cycle of said skip circuit, 5
said kick circuit responsive to movement of said first cam means for initiating incremental changes in the cycle of said skip circuit, said pulse circuit responsive to movement of said first cam means for operation of said bi-directional motor, 10
said multi-station switch including a plurality of sets of contacts that are electrically connected to said spray guns and said skip and reset circuits controlling the operation of said electrical means to control the application of a striping pattern by said spray guns.

3. The road striping machine of claim 2, further characterized by

a pair of multi-position stepping relays with their multiple positions in phase with each other, 20
one of said relays stepped by operator control of said road striping machine, the other of said relays stepped by said kick circuit.

4. The road striping machine of claim 2, further characterized by

said first cam means including a kick cam and a pulse cam controlling said kick circuit and said pulse circuit respectively, 30
a lobe portion on each of said kick and said pulse cams, said lobe portion on said pulse cam correlated with said lobe portion on said kick cam to activate said pulse circuit immediately following activation of said kick circuit.

5. The road striping machinery of claim 4, further characterized by

said pulse cam being split lobe cam in which the amount of lobe portion can be varied.

6. A road striping machine comprising at least one spray gun having a valve operating solenoid, 40 means responsive to movement of said striping machine for controlling the operation of said at least one spray gun, said controlling means including

driving means, electrically controlled clutch means operatively 45 coupled to said driving means,

said clutch means including a clutch and a brake, a first cam means operatively coupled to said driving means,

differential means having one portion coupled to 50 said clutch means,

a bi-directional motor coupled to a second portion of said differential means,

a second cam means operatively coupled to said 55 second portion of said differential means, circuit means operatively connected to said clutch means and said motor,

switch means in said circuit means and operatively connected to said first and second cam means.

7. A road striping machine comprising at least one spray gun having a valve operating solenoid,

means responsive to movement of said striping machine for controlling the operation of said at least one spray gun, 60
said controlling means including

driving means, electrically controlled clutch means operatively 65 coupled to said driving means,

a first cam means operatively coupled to said driving means,

differential means having one portion coupled to 70 said clutch means,

a bi-directional motor coupled to a second portion of said differential means,

a second cam means operatively coupled to said second portion of said differential means, circuit means operatively connected to said clutch means and said motor,

said circuit means including a pair of multi-position stepping relays with their multiple positions in phase with each other, switch means in said circuit means and operatively connected to said first and second cam means.

8. The road striping machine of claim 7, further characterized by

said circuit means further including motor operation relay means and motor direction control relay means operatively connected to said bi-directional motor for turning said motor on and controlling the direction of rotation of said motor.

9. The road striping machine of claim 7, further characterized by

said first cam means including at least two cams each having lobe portions thereon, at least one of said cams having means to adjust the lobe portion thereon, another of said cams leading said at least one of said cams in rotation of said lobe portion thereon.

10. A road striping machine comprising at least one spray gun having a valve operating solenoid,

means responsive to movement of said striping machine for controlling the operation of said at least one spray gun,

said controlling means including driving means,

first electrically controlled clutch means operatively coupled to said driving means,

second electrically controlled clutch means operatively coupled to said driving means by a different gear ratio than the coupling between said first clutch means and said driving means,

a first and second cam means operatively coupled to said driving means and to the input of said first and second clutch means,

a third and a fourth cam means operatively coupled to the outputs of said first and second clutch means.

11. Road striping machinery comprising a ground wheel rotatably mounted on said machine,

a plurality of spray guns mounted on said machine, an electrical circuit responsive to movement of said ground wheel for controlling the operation of said spray guns,

a first cam means operatively connected to turn proportionately to the rotation of said ground wheel, first and second electromagnetic clutch means electrically connected to said electrical circuit and adapted to be operatively connected to said ground wheel,

said second electromagnetic clutch geared to operate from said ground wheel at a higher speed than said first electromagnetic clutch is geared to operate from said ground wheel,

a gear means connected in common to outputs of both said first and second electromagnetic clutch means, a second cam means connected to said gear means for rotation therewith,

said electrical circuit including

a power supply,

a multi-station switch connected to said power supply,

a skip circuit, reset circuit, kick circuit and pulse circuit,

said skip circuit including a switch responsive to movement of said second cam means for intermittently controlling the operation of said guns,

11

said reset circuit responsive to movement of said second cam means for automatically resetting the cycle of said skip circuit,
 said kick circuit responsive to movement of said first cam means for initiating incremental changes in the cycle of said skip circuit,
 said multi-station switch including a plurality of sets of contacts that are electrically connected to said spray guns and said skip and reset circuits controlling the operation of said electrical means to control the application of a striping pattern by said spray guns.
